BOAT CONSTRUCTION

Stannard Stocking, 3 Oliver St., South Norwalk, Conn., and John C. Stocking, 190 Waite St., Hamden, Conn.

Filed Oct. 27, 1964, Ser. No. 406,825

4 Claims. (Cl. 9—6)

The present invention relates to boats and more particularly to an improved hull construction for small boats which may be rowed, sailed, or motor driven.

It is a common practice to moor a boat at a permanent mooring at some distance from the shore and then use a smaller boat for transportation from the shore to the mooring. One form of tender used for this purpose is a "pram" of short length and having flat ends or transoms to increase its beam. Also, other forms of small boats in the range of six feet to sixteen feet in length are used for rowing, sailing and motor propulsion by inboard or outboard motors and may have round, flat or V-shaped bottoms. Such boats, and especially the smaller ones such as prams, are easily tipped and, therefore, are apt to tip over completely or cause a person in the boat to lose his balance and fall from the boat into the water. Furthermore, such boats do not tow nor point well, but instead are apt to pitch and yaw from side to side.

One of the objects of the present invention is to provide a boat of the type indicated with an improved hull construction for materially increasing the stability of the boat against tipping and capsizing.

Another object is to provide an improved construction in a boat to resist yawing while in motion either when propelled by oars or motor, or when towed.

Another object is to provide a boat of the type indicated with a double bottom unsinkable construction without sacrificing otherwise useful space.

Still another object is to provide an improved hull construction for a boat which is of relatively simple and compact construction, economical to manufacture and one which provides maximum stability and minimum drag when moving through the water at normal speeds.

These and other objects will become more apparent from the following description and drawings in which like reference characters denote like parts throughout the several views. It is to be expressly understood, however, that the drawings are for the purpose of illustration only and are not a definition of the limits of the invention, references being had for this purpose to the appended claims.

In the drawings:

FIGURE 1 is a perspective view of a small boat incorporating the novel features of the present invention and showing the spaced sponsons depending from the sides of the hull at the stern of the boat.

FIGURE 2 is a side elevational view of the boat illustrated in FIGURE 1 and showing its attitude with respect to the water line and the sponsons extending forwardly from the stern and merging with the V-shaped bottom at a location greater than one-half the length of the boat from the stern.

FIGURE 3 is a plan view of the boat showing the location of the sponsons, the three centers of buoyancy and drag and the straight lines parallel to the centerline of the boat formed by the ledges at the inner edges of the sponsons.

FIGURE 4 is a transverse sectional view taken on line 4—4 of FIGURE 3 to show the V-shaped form of the hull forwardly of the sponsons.

FIGURE 5 is a transverse sectional view taken on line 5—5 of FIGURE 4 to show the V-shaped bottom and spaced sponsons at the sides of the boat.

FIGURE 6 is a transverse sectional view taken on line

2

6—6 of FIGURE 3 to further show the contour of the bottom of the boat adjacent the stern.

FIGURE 7 is a reproduction of a photograph of the boat illustrated in FIGURE 1 showing the stability of the boat with a person standing at one side, amidship, and holding an outboard motor.

FIGURE 8 is a diagrammatic view of the boat showing the forces acting on the boat tending to cause it to move in a straight line without yawing.

FIGURE 9 is a perspective view of the bottom of a boat of modified construction in which the sponsons incline inwardly toward each other from the sides of the boat.

FIGURE 10 is a perspective view of a further modified construction showing the sponsons of triangular shape and having keel fins projecting from the apexes of the sponsons.

FIGURE 11 is a perspective view of the bottom of a boat of further modified construction in which the V-shaped bottom extends throughout the length of the boat with a depending fin adjacent the stern and flat bottomed sponsons at either side of the curved surfaces therebetween.

FIGURE 12 is a perspective view of a boat similar to the one shown in FIGURE 9 but of modified construction having flat bottomed sponsons with depended fins.

FIGURE 13 is a perspective view of a boat having a bottom of still more modified construction in which the sponsons are curved with depending fins.

30 The invention resides in providing spaced sponsons depending from the sides of a boat which extend forwardly from the stern a distance greater than one-half the length of the boat and which merge with the sides and bottom of the boat. This construction provides three

35 major centers of displacement at the sides and bow of the boat about which the boat is supported. These three centers of support form the apexes of an equilateral triangle having a base line extending across the boat adjacent the stern and sides extending from the ends of the

40 base line forwardly and toward the other point on the centerline of the boat adjacent its bow. The triangle formed between the three points of support is bisected by the centerline of the boat which extends at right angles to the base line of the triangle. These three centers of

45 displacement remain substantially constant for all conditions of loading when motionless and conditions of speed when moving, and in addition, provide a tripod for supporting the boat with greater stability about the loading, boarding and working areas of the boat. The centers 50 of buoyancy at the ends of the base line of the triangle provide side to side stability against rocking and together with the point on the centerline of the boat provide fore and aft stability against pitching.

Furthermore, the sponsons are so formed as to provide ledges projecting downwardly from the bottom of the boat in a direction parallel to the centerline thereof and act as skeg keels to cause the boat to move forwardly in a straight line when towed or propelled by oars, sail or a motor. Also, the three centers of buoyancy constitute three centers of drag to act against the forces tending to cause the boat to yaw as it moves forwardly through the water.

In addition, the improved construction provides a double bottom having an inner floor and an outer shell 65 between which buoyant materials of low specific gravity such as cork, plastic foam, etc. are placed to provide a flat floor deck and leaving all of the space between the sides available for use. The buoyant materials are bonded to both the floor and outer shell to provide a hull of considerable rigidity and strength which lends itself readily to molded plastic of fiberglass construction.

However, the bottom may be made of inner and outer sheets of plywood covered with fiberglass or of sheets of plywood only with appropriate stringers and or ribs to which the floor and outer shell are fastened.

The use of spaced sponsons beside providing stability about the centers of buoyancy also adapts the boat to plane on the surface of the water at relatively low speed without sacrifice of stability since the planing surfaces are widely spaced. It is well recognized that boats equipped with planing surfaces are for many purposes superior to conventional boats since at planing speeds displacement is minimized and drag proportionately reduced. The sponsons of the present invention provide such planing surfaces as well as increasing the stability against tipping, pitching and yawing.

For purposes of illustration the invention is shown applied to a "pram" having flat ends to increase its beam, but it is to be understood that the invention can be used to great advantage in any small boat having a length in the range of six feet to sixteen feet with hulls of various shapes, whether it be used as a row boat, motor boat or sail boat. The pram as shown in FIGURES 1 to 8 comprises sides 2 and 3, front and rear transoms 4 and 5 and a bottom 6. The bottom 6 may be flat, rounded or V-shaped to produce a greater displacement, and instead of a flat transom at the front end, the sides and bottom may be continued as shown in dotted and dash lines in FIGURE 3 to form a rounded or pointed bow. As thus far described the pram is of conventional construction.

In accordance with the present invention, spaced sponsons 7 and 8 depend from the bottom 6 of the boat and extend from the stern transom 5 forwardly for a distance greater than one-half the length of the boat, see FIGURE 2. Preferably the sponsons 7 and 8 extend from the stern to a point about two-thirds the length of the boat. The bottom 6 between the sponsons 7 and 8 is a V-shape, but with the angle decreasing from the stern toward the bow, see FIGURES 4 to 6. The forward end of the sponsons 7 and 8 merge with the V-shaped bottom 6 at their inner edges and gradually curve upwardly until they merge with the bottom from the inner edges outwardly, see FIGURE 2.

As shown most clearly in FIGURES 5 and 6 the sponsons 7 and 8 are of rectangular shape in cross section in the illustrated embodiment and have outer and rearward edges 10, 11 and 12, 13 formed as continuations of the sides 2 and 3 and rear transom 5 below the floor deck 9. The bottom of the sponsons 7 and 8 are flat surfaces which incline upwardly as they extend forwardly from the stern. Thus, the sponsons 7 and 8 have their greatest depth below the floor deck 9 at the stern and are of gradually decreasing depth along their length until they merge with the V-shaped bottom 6 by gradually changing from flat surfaces to the V-shaped bottom as shown most clearly in FIGURE 2. The inner edges of the sponsons 7 and 8 terminate in ledges 14 and 15 extending upwardly to merge with the V-shaped bottom 6 as shown most clearly in FIGURES 5 and 6. Ledges 16 and 17 are filets between the flat bottoms 14 and 15 of the sponsons 7 and 8 and the V-shaped bottom 6 and the ledges gradually decrease in height from the stern toward the bow in accordance with the depth of the sponsons. As will be observed from FIGURES 3, 5 and 6 the ledges 16 and 17 are spaced from each other and from the centerline of the boat and extend in straight lines parallel to the centerline.

The boat has a double bottom construction comprising the floor deck 9 and an outer shell 18 and the sponsons 7 and 8 are formed by a homogeneous body of a buoyant material 19, such as cork, plastic foam, or the like, between the floor deck and shell. The buoyant material 19 is bonded to the floor deck 6 and outer shell 18, as by a thermosetting plastic, to produce a rigid and strong con-

struction. Furthermore, this construction provides an unsinkable boat because of the buoyancy of the material 19 built into the double bottom of the hull. The resulting structure as shown most clearly in FIGURES 4 to 6 has the sponsons 7 and 8 projecting below the V-shaped bottom 6 adjacent the sides thereof and the sponsons are of generally rectangular shape in cross section and decrease in depth from the stern transom 4 forwardly for a distance greater than one-half the length of the boat where they gradually merge with the V-shaped bottom 6. For example, one boat made in accordance with the present invention was eight feet long, four feet wide with each sponson six inches wide at the stern and projecting downwardly four inches below the bottom and of gradually decreasing height and increasing width from the stern forwardly and terminating at a distance of five feet from the stern.

A boat of this construction produces three centers of displacement and therefore buoyancy. Two of these centers of buoyancy are located at the points B and C, as illustrated in FIGURES 2 and 3, while the third point A is located on the centerline of the boat forwardly of the sponsons 7 and 8. These three points A, B and C form, in effect, a triangular area which is bisected by the centerline of the boat. When the boat is loaded within this triangular area it has been found to be very stable against tipping as compared with boats of similar dimensions with a conventional bottom construction. For example, FIGURE 7 is a photolithographed reproduction of a photograph showing one of the inventors standing adjacent the point B in the pram and holding an outboard motor without any substantial tipping of the boat. It is believed that the stability of the boat against rocking is due to the fact that loading of the boat in the triangular area between the points A, B and C will produce a greater displacement by the sponson at opposite sides of the centerline than occurs between the sponsons so that the center of buoyancy does not shift as the boat is moved downwardly into the water, but instead, the three centers of displacement and buoyancy A, B and C remain substantially constant. For example, any loading between the points A, B and C will produce a greater displacement of water in the area surrounding the points A, B and C than at any point therebetween and the force of the load at one point will be distributed to the other centers. Also, the displacement and buoyancy resulting from loading is distributed around the three centers A, B and C to provide stability against fore and aft pitching. Whatever the reasons, the new construction as described above produces a greater stability in small boats against rocking and pitching.

Furthermore, the construction of the sponsons 7 and 8 with spaced ledges 16 and 17 at the inner edges extending in straight lines parallel to each other and the centerline of the boat increases the resistance of the boat to yawing when it is being propelled either by oars, by sails or by motor. It is believed that the reasons for this resistance to yawing is that the parallel ledges 16 and 17 act as keels resisting movement in any direction except in the forward direction of the boat. The points B and C constituting centers of displacement and buoyancy also constitute centers of drag because these points are where the boat is supported against the action of gravity when propelled. The forces acting on the points B and C on the bottom of applicants' boat when it tends to yaw are illustrated in FIGURE 8. If the boat tends to yaw to the right as indicated by the centerline of the boat with respect to the direction in which it is propelled as indicated by the horizontal line D, a force couple is produced around said line of direction D at the points B and C. The drag produced on the points B and C would be substantially the same, but the moment arm M between the drag point B and the line of direction D is shorter than the moment arm M-1 acting between the drag point C and the line of direction of the boat. Thus as

the product of the force and moment arm $M-1$ is greater than the product of the force and moment arm M , the resulting force tends to rotate the boat in a counter-clockwise direction until the centerline of the boat corresponds with the line of direction D . If the boat tends to yaw to the left the reverse situation would exist. The only equilibrium position where the forces acting on the points B and C are equal and opposite is when the centerline of the boat coincides with its line of direction D . Applicants' improved construction, therefore, in addition to increasing stability against rocking and pitching also increases the stability of the boat against yawing.

In addition to increasing the stability of the boat against rocking, pitching and yawing, the flat bottoms 14 and 15 of the sponsons 7 and 8 provide planing surfaces on which the boat rides when propelled forwardly either by oars, sails or a motor. A forward force applied to the boat will cause it to ride up on the surface of the water to a higher level than when the boat is motionless. The reason for this is the tendency of the inclined planes formed by the flat bottoms 14 and 15 of the sponsons 7 and 8 to ride out of the water. As the area of the bottom 6 of the boat in contact with the water decreases as it planes, the resistance to forward motion decreases. The centers of the forces acting on the bottom of the sponsons 7 and 8 are then located at points B and C and act as centers of drag when the boat is propelled at moderate speed.

FIGURE 9 illustrates a boat of modified construction incorporating the novel features of the present invention. In FIGURE 9 the bottom of the boat has a V-shaped construction 24 at its forward end for approximately one-third of its length and an inverted V-shaped construction 25 for the rearward two-thirds of its length. The sponsons 26 and 27 project downwardly as continuations of the sides 28 , 29 and transom 30 the same as in the construction illustrated in FIGURES 1 to 8, but the sponsons incline inwardly from the edges to form the inverted V-shaped section 25 . Each of the sponsons 26 and 27 has a fin 31 and 32 , respectively depending from the outer edge thereof.

FIGURE 10 illustrates a further modified construction having a V-shaped bottom section adjacent its forward end and an inverted V-shaped section rearwardly of the V-shaped section the same as in FIGURE 9. The sponsons 35 and 36 , however, are of generally triangular shape in cross-section having apexes 37 and 38 inwardly from the sides of the boat. Fins 39 and 40 depend from the apexes 37 and 38 of the sponsons 35 and 36 adjacent the rearward ends thereof.

FIGURE 11 illustrates a further modified construction in which flat bottomed sponsons 43 and 44 depend from the sides of the boat with a V-shaped bottom section therebetween the same as the sponsons 7 and 8 and V-shaped bottom 6 in the boat illustrated in FIGURES 1 to 8. However, between the inner edges of the sponsons 43 and 44 and the V-shaped center portion 45 of the boat the bottom has curved surfaces 46 and 47 . In addition a fin keel 48 projects downwardly from the V-shaped center portion of the hull adjacent its rearward end.

FIGURE 12 illustrates a further modified construction having a reverse V-shaped bottom as in the construction illustrated in FIGURES 9 and 10, but with flat bottomed sponsons 50 and 51 as illustrated in FIGURES 1 to 8

and fins 52 and 53 depending from the center of the flat bottom sponsons.

FIGURE 13 illustrates a still further modified construction in which the sponsons 55 and 56 are of a curved contour with depending fins 57 and 58 and a reversely curved section 59 between the curved sponsons.

It will now be observed that the present invention provides an improved hull construction for small boats that materially increase the stability of the boat against tipping, pitching and yawing. It will also be observed that the present invention provides an unsinkable boat with a double bottom construction without sacrificing otherwise useful space in the boat. It will still further be observed that the invention provides an improved hull construction for a boat which is of relatively simple and compact construction that may be economically manufactured, and one which provides maximum stability and minimum drag when moving through the water at normal speeds.

While several forms of construction are herein illustrated and described it will be understood that further changes may be made in the construction and arrangement of elements without departing from the spirit or scope of the invention. Therefore without limitation in this respect the invention is defined in the following claims.

We claim:

1. A boat having sides, a V-shaped bottom extending throughout its length and of a gradually decreasing angle from the stern to the forward end, sponsons depending from the sides of the boat in spaced relation at opposite sides of its centerline and extending forwardly from the stern for substantially two-thirds the length of the boat, said sponsons having flat surfaces at the bottom tapering from a maximum depth at the stern until they merge with the V-shaped bottom, the inner edges of the sponsons being parallel to the centerline of the boat and forming ledges merging with the V-shaped bottom, said sponsons at the stern and V-shaped bottom at the forward end of the boat providing three substantially constant centers of buoyancy and drag at the apexes of an equilateral triangle bisected by the centerline of the boat whereby to stabilize the boat against tipping, pitching and yawing when propelled and towed.

2. A boat in accordance with claim 1 having a double bottom comprising an inner floor and outer shell around the sponsons, and the space between the inner floor and outer shell containing a buoyant material.

3. A boat in accordance with claim 2 in which the inner floor and outer shell are formed of fiberglass coated with a thermo-setting plastic.

4. A boat in accordance with claim 1 having flat ends connected to the bottom and sides.
